United States Patent Office.

WILLIAM J. HOWARD, OF PETERSBURG, KENTUCKY.

Design No. 2,710, dated July 23, 1867.

DESIGN FOR A CASTER-COVERING.

The Schedule referred to in these Letters Patent and making part of the same.

TO ALL WHOM IT MAY CONCERN:

Be it known that I, WILLIAM J. HOWARD, of Petersburg, in the county of Boone, and State of Kentucky, have invented a new Design for a Caster-Covering, of which the following is a full, clear, and exact description, reference being had to the accompanying drawings, forming part of this specification, in which the figure is a side view of the caster, showing my improved covering.

A is the shank or pivot, and B is the roller of an ordinary caster. C is the covering, which may be formed upon or attached to the caster, or which may be permanently attached to the article of furniture. The covering C may be cast, or struck up out of the sheet metal, or carved. c^1 is a circular horizontal plate or shoulder, from the under side of the outer edge of which descends a series of lobes or elongated projections c^2 , from the lower edge of the lower ends of which descends another series of lobes or elongated projections c^3 , similar to the series c^2 , but larger, thus forming a groove or shoulder around the covering B, as shown in the drawing.

I claim as new, and desire to secure by Letters Patent—

The design for an ornamental furniture-caster covering, substantially as herein shown and described.

WILLIAM J. HOWARD.
